(57) CLAIM

The ornamental design for an illuminated magnifier, as shown and described.

DESCRIPTION

FIG. 1 is a perspective elevational view of an illuminated magnifier showing my new design;

FIG. 2 is a top plan view of the illuminated magnifier;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a front elevational view thereof.

Wherein the broken line showing of a battery compartment cover, a switch, a power connector and a light source are for illustrative purposes only and form no part of my design.
